CLAIM

The ornamental design for a prosthetic heart valve element, as shown and described.

DESCRIPTION

FIG. 1 is a perspective view from above of a prosthetic heart valve element showing a first embodiment of our new design;

FIG. 2 is a perspective view from below thereof;

FIG. 3 is a front side view thereof;

FIG. 4 is a left side view thereof;

FIG. 5 is a top plan view thereof; and,

FIG. 6 is a bottom plan view thereof.

The broken line showing is included for the purpose of illustrating unclaimed subject matter and forms no part of the claimed design.
